UNITED STATES PATENT OFFICE

KENNETH HOWIE, OF NORRISTOWN, PENNSYLVANIA, ASSIGNOR TO WILDMAN MFG. CO., OF NORRISTOWN, PENNSYLVANIA, A CORPORATION OF PENNSYLVANIA

STOP FOR PREVENTING REBOUND OF CARRIER RODS OF FULL-FASHIONED-KNITTING MACHINES

Application filed January 6, 1928. Serial No. 244,975.

This invention relates to a stop for a carrier bar, for instance, a thread guide carrier bar for a full fashioned knitting machine.

An object of the invention is to prevent rebound of the bar at the end of its stroke.

Other objects will appear hereinafter, from the accompanying description, drawing and claims.

The invention consists in the features, combination and arrangement of parts herein-after described and particularly pointed out in the claims.

In the accompanying drawings

Figure 1 is a view of my catch device for the carrier rod shown in position relative to said carrier rod.

Fig. 2 is an end view of a portion of a full fashioned knitting machine showing the catch devices of my invention mounted one on each of the carrier bars.

Referring to the drawings, C represents the yarn carrier rod mounted in the machine in the usual manner, and adapted to be stopped at the end of its stroke by the usual adjustable abutment F.

The carrier rod C is provided at its upper edge adjacent its end or at other locations with an insert member G of hardened steel, held to the carrier rod by screws H. The wedge roller B of the catch device D is adapted to engage and bear upon the top of the insert member G upon there being any tendency to rebound after the carrier rod has been stopped by the abutment F.

The roller B upon rebound tendency of the carrier rod C after striking the abutment F, is in contact with the insert member G of rod C and also with the fixed hardened steel incline member K and will be frictionally wedged between K and C, by reason of their angular relation, thus stopping rebound movement of rod C.

The catch device D comprises the hardened steel incline member K adapted to be fixed in any suitable manner to the machine, the member K having a depending lug L provided with a bore M for slidably receiving the stem N at one end of which the roller B is mounted. The stem N is provided at its opposite end with an annular flange O between which

and the lug L a coil spring E surrounding the stem is interposed. The end P of the stem N forms a contact against which the contact Q of the catch release lever A is adapted to engage to throw the catch out of operation against the action of spring E, and after the catch has operated to prevent rebound of bar C, by pushing the wedge roller B out of wedging contact with incline K.

A similar catch device may be provided at the opposite end of the carrier bar and suitable actuating means and timing regulation provided for controlling the release lever A. The lever A is pivotally mounted at S to any suitable part of the machine and may be connected to a cam on the main cam shaft of the knitting machine, or other suitable actuating means may be provided. The spring E tends to bring the wedge roller into contact with incline K while in contact with the insert G of rod C and when the lever A is retracted from throw-out position by suitable timing or cam mechanism, the catch will be restored to operative position to prevent rebound.

Modifications such as the substitution of an ordinary wedge for the roller B is contemplated by the present invention and is within the scope thereof.

It will be understood that as in usual practice in full fashioned knitting machines of the Cotton type, the carrier bars are reciprocated lengthwise of the machine by so called frictions consisting of driving members having frictional engagement with the carrier bars. Unless means are provided to prevent rebound of the carrier bars when they strike their stops, said bars will become displaced relative to the frictions and it is to avoid this action that the above described arresting device is provided.

The wedge B is in operative position with relation to rod C during the entire inward travel of the yarn carrier rod C.

I claim:

1. In a full fashioned knitting machine, a friction stop for preventing rebound of the yarn carrier rod at the end of its stroke, said stop comprising an incline member having an inclined lower surface disposed at an

- angle to the yarn carrier rod, a wedge mov-
ably mounted adjacent said incline member
and adapted to engage both the inclined sur-
face and the top of the carrier rod to prevent
rebound of the carrier rod.
- 5 2. In a full fashioned knitting machine,
a friction stop for preventing rebound of the
yarn carrier rod at the end of its stroke, said
stop comprising an incline member having
10 an inclined lower surface disposed in angu-
lar relation to the top of the yarn carrier
rod, and a wedge adapted to contact with the
inclined surface and the top of the carrier
rod to prevent rebound of the carrier rod.
- 15 3. In a full fashioned knitting machine, a
friction stop for preventing rebound of the
yarn carrier rod at the end of its stroke, said
stop comprising an incline member having
20 an inclined lower surface disposed in angu-
lar relation to the top of the yarn carrier
rod, and a wedge adapted to contact with the
inclined surface and the top of the carrier
rod to prevent rebound of the carrier rod and
means for actuating said wedge.
- 25 4. Apparatus according to claim 3 in
which said wedge actuating means includes
a lever arm pivotally mounted to the knitting
machine and operated by suitable mecha-
nism to push said wedge out of contact with
30 said inclined surface, and a spring connected
with said wedge to urge it into wedged posi-
tion between the surfaces.
- 35 5. In a full fashioned knitting machine, a
friction stop for preventing rebound of the
yarn carrier rod at the end of its stroke, said
stop comprising an incline member having an
inclined lower surface disposed at an angle
40 to the top of the yarn carrier rod, a wedge,
a shaft connected to said wedge, said incline
member having a bore for slidably receiv-
ing said wedge shaft, means adapted to en-
gage said wedge shaft to move the wedge out
45 of wedged position between the inclined sur-
face and the top of the carrier rod, and spring
means engaging the wedge shaft for urging
the wedge into wedged position.
- 50 6. Apparatus according to claim 5 in which
said means for moving the wedge out of
wedged position, comprises an arm pivotally
mounted on the knitting machine and adapt-
ed to be swung against said wedge shaft to
55 move the same.
7. Apparatus according to claim 5 in which
said wedge comprises a roller mounted on
the end of the wedge shaft and adapted to
roll into and out of wedged position upon the
top of the carrier bar.
- 60 8. Apparatus according to claim 5 in which
said inclined surface and the wedge engaging
surface of the carrier rod are of hardened
steel.
- 65 9. In a full fashioned knitting machine, a
friction driven yarn carrier rod and stop
means including means independent of the
friction box drive for preventing rebound of
the carrier rod and displacement relative to
the friction driving mechanism.
- 70 10. In a full fashioned knitting machine,
a friction driven yarn carrier rod and stop
means including friction means independent
of the friction box drive for preventing re-
bound of the carrier rod and preventing dis-
placement relative to the friction driving
mechanism.
- 75 11. Apparatus according to claim 10 in
which said friction means comprises a wedge
for frictionally preventing rebound of the
yarn carrier rod.
- 80 12. In connection with the rebound pre-
venting means of claim 9, means for auto-
matically releasing the same.
- 85 13. In a full fashioned knitting machine,
in combination, a friction driven yarn car-
rier rod, a stop for arresting the rod, a fric-
tion catch for preventing rebound, said fric-
tion catch being independent of the friction
box drive, and releasing means for said fric-
tion catch.
- In testimony whereof, I affix my signature,
KENNETH HOWIE. 90
